Primary Examiner — Jennifer L Rempfer*Assistant Examiner* — Adrienne Corra(74) *Attorney, Agent, or Firm* — Banner & Witcoff, Ltd.(57) **CLAIM**

The ornamental design for a shoe, as shown and described.

DESCRIPTION

FIG. 1 is a bottom view of a shoe showing our new design; FIG. 2 is a bottom front perspective view thereof; and, FIG. 3 is a bottom rear perspective view thereof. The broken lines within the shaded areas form no part of the claimed design. The broken lines depicting the remainder of the shoe form no part of the claimed design.

1 Claim, 3 Drawing Sheets(56)
